Monika J. Hassell(57) **CLAIM**

The ornamental design for a removable railing tray, as shown and described.

DESCRIPTION

FIG. 1 is a top view of a removable railing tray showing our new design.

FIG. 2 is a side view of a portion of the removable railing tray (without showing the front and back edges thereof) taken along line 2-2 in FIG. 1, as installed on the deck railing (shown in broken lines); and,

FIG. 3 is a detailed sectional view of the edge trim detail that traverses the circumference of the removable tray.

The broken lines in FIG. 2 are for illustrative purposes only and form no part of the claimed design.
